UNITED STATES PATENT OFFICE.

KAZIMIERZ ZAWADZINSKI, OF WADOWICE, AUSTRIA-HUNGARY.

ROAD-ROLLER.

1,088,509.

Specification of Letters Patent.

Patented Feb. 24, 1914.

Application filed June 30, 1913. Serial No. 776,712.

To all whom it may concern:

Be it known that I, KAZIMIERZ ZAWADZINSKI, a subject of the Austro-Hungarian Emperor, and residing at Wadowice, Galicia, Austria-Hungary, have invented certain new and useful Improvements in Road-Rollers, of which the following is a specification.

My invention relates to road rollers.

Road rollers heretofore in general use *i. e.* both horse-rollers and steam-rollers, have the defect that the specific pressure applied to the surface of the road-facing can be varied only within small limits. This is because changes in the specific pressure of such rollers are made by increasing the weight of the roller, this being generally effected in the case of horse-rollers by means of sand or water, and in the case of steam-rollers by blocks of iron. An increase in specific pressure which is brought about by an increase in weight, however, permits gradual compression of the road-facing only to a limited extent, because these rollers can exert pressure only on a supporting surface of constant area, and the specific pressure can be increased only so far as is permitted by the weight added to the roller and so far as this added weight can come wholly into operation per unit area. In the case of horse-rollers, the added weight is limited by the power of the horse. For this reason the weight of this type of roller is at most 10 tons. To obtain a greater specific load on the road-facing to be rolled, steam-rollers are therefore employed, the weight of which may indeed amount to 20 tons. This type of roller has, however, the disadvantage that the weight can be increased to a much smaller extent than in the case of horse-rollers, the limitation being due to the necessarily heavy weight of material required for the construction of the steam-roller itself. Moreover, a steam-roller has the drawback that, owing to the specific pressure being too great at the beginning of rolling, this roller cannot exercise a gradual and long-range compression on the road-facing which is being rolled. The undulations in the gravel, which are distinctly visible *e. g.* in front of the roller, are ample proof that the facing of gravel, though it has already been somewhat compressed, is again broken up, to be then crushed and firmly compressed. In many cases therefore in order to be able successfully to roll the road-facing, the lighter horse-roller has had to be first used, its

weight being gradually increased, and only then could the steam-roller be employed. Moreover, the steam-roller is an expensive appliance which on that account is not accessible to every road-builder. The fuel requisite therefor as well as the attendants required involve a heavy outlay. Moreover, bridges and so on must be built with a view to supporting the heavy weight of steam-rollers, and therefore a greater weight than would be needed for the normal traffic on the road, whereby the cost of road building is uselessly increased, the more so as the passage of such rollers over it frequently necessitates the road being repaired from time to time. Further, the method of gradually loading the rollers of either of the above-named types by means of blocks of iron, sand and water must likewise be regarded as exceedingly disadvantageous, as these auxiliaries must be always kept at disposal and consequently have to be first conveyed to the spot.

A primary object of my invention is to obviate the above-described defects, all of which are well-known to everyone versed in the art. To this end, I provide a roller, the novel essential feature of which is that, while the weight is kept constant, the specific surface-pressure in the direction of the thrust is increased or diminished by changing the diameter of the roller.

One illustrative embodiment of my invention is represented by way of example in the accompanying drawing, wherein:

Figure 1 is a sectional end elevation, Fig. 2 is a vertical longitudinal section, Fig. 3 an end elevation according to Figs. 1 and 2, and Fig. 4 an end elevation showing the roller when one of the smaller auxiliary rollers is in operation.

As is well known, the specific surface-pressure of a roller is dependent on the weight of the roller and the area of the supporting surface. The latter again depends not only on the width of the roller and the elasticity of the materials on which it rests but also on the diameter of the roller. If therefore a high specific surface-pressure of the roller is desired, it suffices, instead of increasing the weight of the roller, to keep the weight constant and reduce the diameter. In the example illustrated, the reduction of the diameter of the roller is obtained owing to the complete device comprising two, three or more rollers, of which the largest in-

closes the others, and the latter serve then as weights. The rollers are so arranged that it is possible to roll by means of each of them, the entire weight of the complete device being transmitted to the working roller.

Referring to the drawing, *a* represents the main drum or iron roller having dimensions corresponding to those of the ordinary horse-roller; *b*, *c* represent two auxiliary rollers, the diameter of which is smaller than that of the main roller *a*. The appliance is so designed that the auxiliary rollers do not hinder the action of the main roller *a*, these auxiliary rollers being located inside the latter. The number of auxiliary rollers may of course be as large as desired provided that the chamber in the main roller can contain them, it being manifestly desirable to increase the specific load applied to the ground gradually, *i. e.* in as many stages as possible. The auxiliary rollers mounted in the said chamber must however, on practical grounds, be so distributed, and the weight of the same be so chosen, that when roller *a* is working, the center of gravity of the complete device is located in the axis of this roller because, if not, disturbances due to the want of balance would arise, which would have a detrimental influence both on the working of the roller and on the draft-animal or driving engine.

The roller *a* may be provided either with a shaft extending axially throughout its length, or, as in Figs. 1 and 2, be journaled by means of pins *c* in bearings *d*, which are integral with the frame *e*. The portions *f*, *g* of the crown of the roller *a*, which are located outside the auxiliary rollers, can be removed in order to allow the auxiliary rollers to project beyond the peripheral surface of the roller *a* (Fig. 4).

After, for example, the gravel facing of the road has been compressed by the main roller *a*, a change is made whereby the next smaller roller, *b* in Fig. 1, is put into operation. The latter roller is journaled in the end walls of the roller *a*, so as to be transversely slidable therein, it being possible for these end walls to have spokes because there is no need to seal the inner chamber of the roller *a*. The bearings *h* which journal the roller *b* are slid able in elongated apertures *h* and can be displaced such a distance that the auxiliary roller *b* projects beyond the crown of the roller *a*, where it is held in position by means of keys or wedges *i*. No difficulty arises in changing the position of the auxiliary roller. The auxiliary roller *b* being at the top, the key *i* is withdrawn, and when the roller *a* is again rotated the auxiliary roller *b* falls by gravity as far outward as the aperture *h* permits. The key is thereupon again put into place, but now on the other side of the bearing *h*.

When the roller *a* is still further rotated the weight of the entire device is borne by the roller *b*. When this position is obtained, the roller *a* must be held fast. This is effected in a simple manner by inserting keys into the holes *n* which are suitably located in the end walls of the main roller *a*.

The keys bear at their projecting ends against the frame *e* and prevent the roller *a* rotating, so that now only the auxiliary roller *b* does the rolling work. As Figs. 3 and 4 show, several of such holes are preferably provided, so that the center of gravity of the entire device can be removed from the point of support of the auxiliary roller *b* in one direction or the other, in order to thus obtain stable balance with the aid of the second point of support which is furnished by the frame and the horses therein. After the roller *b* has been used for rolling for the necessary length of time, the roller *c* with a still smaller diameter can be similarly brought into action, the roller *b* being then pushed back.

The above-described road-roller admits of the employment of a braking device of any suitable construction both for the main roller as well as for the auxiliary rollers, and either the crowns or the end walls of the rollers may be used for the purpose. Scrapers can also be arranged in any suitable manner. The attendance required for my new device involves little time and at most the employment of two men, so that expenses in this respect are reduced to a minimum. Finally it may be pointed out that the smaller width of the auxiliary rollers serves to still further increase the specific load. Moreover, this device is suitable for being driven in any manner, whether by horse, by steam-engine or by petrol-engine; in the two latter cases the motion of the engine can be imparted by suitable transmission means to the axle of the operative roller after adjustment of the latter. Both the dimensions and weight of the device can be chosen within desired limits to suit the purpose of employment and the tractive force at disposal.

I claim:—

1. In a road roller, the combination with a frame, of a plurality of rollers progressively increasing in diameter rotatably mounted therein, and means for holding all the rollers but one in an inoperative position.

2. In a road roller, the combination with a frame, of a plurality of rollers progressively increasing in diameter rotatably mounted therein, the largest roller normally surrounding the remaining rollers and means for holding all the rollers but one in an inoperative position.

3. In a road roller, the combination with a frame, of a plurality of rollers progressively

increasing in diameter rotatably mounted therein, the largest roller normally surrounding the remaining rollers and means for holding all the rollers but one in an inoperative position; the largest roller having one or more removable portions of its periphery for allowing the one or more smaller rollers to project beyond the said periphery.

4. In a road roller, the combination with a frame, of a main roller journaled therein, said main roller having removable plates in its periphery and elongated radial apertures in its end walls, a plurality of auxiliary rollers of different diameters journaled radially displaceable in said apertures, and keys for holding said auxiliary rollers in said apertures.

5. In a road roller, the combination with a frame, of a plurality of rollers progressively increasing in diameter rotatably mounted therein, the largest roller normally surrounding the remaining rollers and means for holding all the rollers but one in an inoperative position; the largest roller having one or more removable portions of its periphery for allowing the one or more smaller

rollers to project beyond the said periphery; and means for fastening the largest roller to said frame in predetermined positions relatively thereto.

6. In a road roller, the combination with a frame, of a plurality of rollers progressively increasing in diameter rotatably mounted therein, the largest roller normally surrounding the remaining rollers and having a plurality of stop-holes in its end wall, and means for holding all the rollers but one in an inoperative position; the largest roller having one or more removable portions of its periphery for allowing the one or more smaller rollers to project beyond the said periphery; and keys engaging in said holes and bearing against said frame for holding the largest roller in a predetermined position.

In testimony whereof I affix my signature in presence of two witnesses.
